UNITED STATES PATENT OFFICE.

WILLIAM G. A. BONWILL, OF PHILADELPHIA, PENNSYLVANIA, ASSIGNOR TO
THE S. S. WHITE DENTAL MANUFACTURING COMPANY, OF SAME PLACE.

ROCK-DRILL AND INSTRUMENT USING REVOLVING HAMMERS.

SPECIFICATION forming part of Letters Patent No. 425,737, dated April 15, 1890.

Application filed December 21, 1886. Serial No. 222,205. (No model.)

To all whom it may concern:

Be it known that I, WILLIAM G. A. BONWILL, a citizen of the United States, residing at Philadelphia, in the county of Philadelphia and State of Pennsylvania, have invented certain new and useful Improvements in Rock-Drills and Instruments Using Revolving Hammers; and I do hereby declare the following to be a full, clear, and exact description of the invention, such as will enable others skilled in the art to which it appertains to make and use the same.

My invention relates to improvements in rock-drills and other instruments using a revolving hammer—such, for instance, as dental pluggers. The revolving hammer is a rapidly-revolving wheel or part having a hammer lug or projection on its periphery, which at every revolution of the wheel strikes upon the end of a tool-carrying spindle, so as to impart a rapid succession of blows thereto and enable the tool at the opposite end of the spindle to do its work.

The object of my invention is to improve the construction of instruments of this class, so that they are better adapted for the performance of the work for which they are intended.

The subject-matter claimed herein as my invention is first described in detail as embodied and organized in the best way now known to me, and is then distinctly recited in the claims at the close of this specification.

In the accompanying drawings, which show my improvements as organized more particularly for use as a rock-drill, Figure 1 is a view in side elevation of the improved instrument. Fig. 2 is a like view at right angles to that depicted in Fig. 1, partly in longitudinal section. Fig. 3 is a side view of the revolving hammer detached; and Fig. 4, a side and an end view of said hammer, showing a modification of the hammer projection thereof. Fig. 5 is a side view of a modification of the instrument, showing it as adapted for operation by manual power through crank-handles and toothed gearing.

A forked frame A is fitted with a transverse axle pin or shaft *a*, with which a revolving hammer wheel or arm B is fitted to revolve

freely when driven by a cord or belt pulley C, connected with the said hammer-wheel or by any other suitable form of gearing with the driving-power. I prefer to use the belt-pulley and a driving band or belt to drive the rotating hammer wheel or arm B when the instrument is to be moved freely about in operation. Jointed or journaled to the outer ends of the revolving axle or shaft *a* of the revolving wheel B is the forked butt-end or rear section D of the hand-piece casing H P C, whereby said hand-piece casing may be rocked freely around its pivotal connection with the frame A. The front end of said forked section D is tubular and internally screw-threaded to receive the male threads of the rear end of the section E of the hand-piece casing. Fitted upon the front end of the casing-section E is the rear end of the front casing-section F, which constitutes the finger-piece or handle-section of the instrument. Said section F is fitted to turn freely on the front end of the section E, preferably by forming an annular groove *f* in said section F to receive a shoulder *g* of a plate G, attached to the section E by fastening-screws, for example.

The tool-carrying spindle H is fitted to have a slight endwise movement in the hand-piece casing, the extent of which may be determined by means of an annular groove *h* in said tool-carrying spindle, which is fitted to receive the reduced end or lug *g'* on the plate G, which projects through a suitable opening in the casing-section E. In addition to the endwise movement or reciprocation of the tool-carrying spindle H in the hand-piece casing it has a revolving motion in the casing-section E, while the front or hand-piece section F is keyed to said tool-carrying spindle, so as to turn with it without interfering with the endwise movement of said spindle in said front section F. This is permitted by means of a longitudinal groove *h'*, (shown by dotted lines in Fig. 2,) in which the point of a set-screw *f'*, passing through said section F, engages. It will therefore be understood that in the preferred organization the tool-carrying spindle has an endwise movement through the whole of the hand-piece casing

and a rotary movement in said casing, except as to its front section, which turns with the spindle.

5 The front end of the tool-carrying spindle H is socketed to receive the shanks of the operating-tools, and is slotted longitudinally, so as to form spring clamping-jaws, and is threaded externally to receive a clamping-nut H', whereby the walls of the tool-sockets 10 may be clamped upon the tool-shank to lock it firmly in the tool-carrying spindle. This tool-locking construction of the front end of the spindle is not claimed herein, as it is a well-known tool-locking device in the art.

15 The periphery of the revolving hammer wheel or arm B is fitted with a hammer projection b, which in the revolution of said wheel strikes upon the end of the tool-carrying spindle H to impart a series of rapid 20 blows thereto. This, broadly, is old; but I have improved the hammer projection in that, instead of a rigid projection or a hammer projection sliding radially, both of which are objectionable, I provide the said projection in 25 the form of a revolving projection, preferably a roller, the curved periphery of which stands out from the periphery of the revolving wheel or arm, so as to strike upon the end of the tool-carrying spindle to impart the blows 30 thereto. The effect of the blows delivered by my roller-hammer projection, instead of the fixed or sliding projection, as heretofore, is substantially different, in that with the old forms of hammer projection a large portion 35 of the blow was taken up by a side blow on the spindle and lateral thrust against the casing, while by my improvement the blow is a rolling one, almost wholly avoiding the side blow or thrust, while acting more effectively 40 in imparting the blows which drive the spindle endwise. The blows are more distinct and positive than where the rigid or sliding hammer projection is employed.

45 The manner of attaching the rolling hammer projection in the periphery of the revolving hammer wheel or arm is immaterial, so long as it has a revolving or rolling motion in said wheel. For instance, in Fig. 3 I have shown a roller extending across the periphery of the hammer-wheel B and retained in place by side plates attached to said wheel, and in Fig. 4 the rolling hammer projection is shown as consisting of a small wheel let 50 into the periphery of the hammer wheel or arm B and secured by an axis-pin passing through the side of said wheel or arm B.

55 Fitted upon the revolving axle or shaft a of the hammer-wheel B is a cam a', working in a yoke or strap i of a vibrating lever I,

pivoted at i' and carrying at its opposite end 60 a spring-pawl i², fitted to engage with a circular series of ratchet-teeth h² on the end of the reciprocating spindle II, whereby as the hammer-wheel is revolved the lever I is vibrated once for each revolution of said wheel 65 and the tool-carrying spindle is turned for each of said revolutions a distance of one ratchet-tooth. It will therefore be seen that during the rotation of the hammer-wheel the spindle H is hit a rapid series of blows, and 70 at the same time gradually turns to present the point of the operating-tool in different relations to the material operated upon.

A modified form of the instrument is shown 75 in Fig. 5, in that it is driven by crank-handles and gearing and is provided with a stationary base or tripod.

While I prefer the construction above described of my improvements embodied in an instrument the spindle of which may be intermittently rotated during the delivery of the blows by the pawl-and-ratchet device described, such device and features form no part of my present invention and are not new with me, my present invention being directed 85 to the rolling-hammer-projection features, as set out in the following claims.

I claim herein as my invention—

1. In a revolving hammer-tool, the combination, substantially as hereinbefore set forth, 90 with a revolving hammer, of a spindle fitted to be struck its intermittent operating-blows by said hammer and an intermediate rolling hammer projection through which the blows of said hammer are communicated to said 95 spindle.

2. The combination, substantially as hereinbefore set forth, of a frame, a revolving hammer fitted thereto, a peripheral rolling hammer projection of said hammer, a tubular 100 casing, and a tool-carrying spindle fitted to reciprocate in said casing and having its butt-end fitted to be struck by said roller projection of the revolving hammer, for the purposes set forth.

105 3. In a revolving hammer-tool, the combination of a bit-actuating spindle, an impact-wheel, and a roller or sphere which is housed within said wheel and a portion of the periphery or surface of which projects beyond the periphery of said impact-wheel, substantially as described.

In testimony whereof I affix my signature in presence of two witnesses.

WM. G. A. BONWILL.
